UNITED STATES PATENT OFFICE.

FRANK B. NIHART, OF BAY MINETTE, ALABAMA.

WINDOW-FASTENER FOR AUTO-CURTAINS.

1,382,666.

Specification of Letters Patent. Patented June 28, 1921.

Application filed May 7, 1918. Serial No. 233,080.

To all whom it may concern:
Be it known that I, FRANK B. NIHART, a citizen of the United States, residing at Bay Minette, in the county of Baldwin, State 5 of Alabama, have invented certain new and useful Improvements in Window-Fasteners for Auto-Curtains; and I do hereby declare the following to be a full, clear, and exact description of the invention, such as will enable others skilled in the art to which it 10 pertains to make and use the same.

The present invention relates to new and useful improvements in means for securing a window of flexible transparent material 15 in a flexible sheet such as the curtain of an automobile.

With the present method of securing the window, by sewing it to the curtain, it is necessary upon breakage of the window such 20 as often occurs, to remove the entire curtain for replacement of the window. It is the object of the present invention to provide a means whereby such a window may be attached to a curtain or removed therefrom 25 in a most ready manner and without necessitating removal of the curtain from the automobile top or other support therefor.

A further object of the invention resides in the provision of a window securing means 30 which serves also as an efficient bracing means for the adjacent portions of the curtain and for the edge portions of the window, to lessen the possibility of breaking or tearing the window.

With the above and other objects and advantages in view, the invention resides more particularly in the novel combination, formation and arrangement of parts herein-after described and particularly pointed out 40 in the appended claim.

In the accompanying drawings:

Figure 1 is an elevational view of a portion of an automobile curtain having a flexible window sheet secured therein by the im- 45 proved securing means.

Fig. 2 is a transverse section.

Fig. 3 is a fragmentary perspective view of one of the body parts of the window at- 50 taching frame bars.

Referring now more particularly to the drawings, 5 designates a portion of an automobile curtain, provided with the usual opening for the reception of a window of celluloid or other suitable transparent and 55 preferably somewhat flexible material. My improved fastening device for the window

6 comprises a rectangular frame permanently secured to the edge portions of the curtain at the window opening, this frame comprising top and bottom sections and 60 pairs of side sections, the adjacent portions of the sections being spaced slightly apart and having flexible connections afforded by the intervening portions of the curtain body. The frame is thus provided with four sets 65 of horizontally acting joints, and may be folded with the curtain. The sections of the frame are each formed from a single elongated plate of metal, preferably pressed steel, the plate being bent longitudinally 70 upon itself adjacent its center. The side 7 of the plate at the inner side of the curtain is plane. The other side is folded or bent up at 12, and is extended inwardly from the bend for a slight distance in a strip 7' 75 nearly or fully contacting with the side 7; it is then directed abruptly away from said side in a shoulder 9 forming a rabbet, and is finally extended in a strip 10 toward the free edge of the side 7, said strip or portion 80 10 being transversely bowed. The edge of the curtain is inserted between the sides and is grippingly engaged by the free edges of said sides by means of rivets 11 passed through the bowed portion 10, the edge of the cur- 85 tain and the side 7.

The transversely bowed part of the portion 10 has a resilient co-operative action in connection with the inner side 7, whereby the curtain is gripped therebetween in a positive 90 manner, and the ingress of water to the interior of the plate is prevented. The edge of the window 6 is disposed in the rabbet and on the portion 7' is clamped thereagainst by a transversely arcuate resilient metal strip 8 95 through which is passed a plurality of screws 13 which are also passed through the edge portion of the window and threaded into the side 7, a double thickness of metal being thus procured at this point to se- 100 curely engage the threads of the screws. The transverse curvature of the strip 8 permits it to be flexed to cause its inner edge to firmly clamp the window in the rabbet, and the outer edge of the strip abuts the shoul- 105 der 9 to effect a tight seam preventing pos- sible ingress of water to the interior of the strip.

To remove and replace the window 6, it is thus merely necessary to remove the screws 110 13 and the strips. An exceedingly simple and effective device has thus been provided

whereby replacement of the window may be effected without the necessity of removing the curtain from its support, and the fastening device presents a neat and attractive 5 appearance.

The transverse curvature of the portion 10 of the plate in addition to affording a desired gripping resiliency, also materially braces the plate against transverse bending 10 stresses such as might frequently occur in use, and the plates forming the sides of the window frame, particularly when thus braced, afford an efficient and valuable bracing means for the curtain and for the window 15 down.

What is claimed is:

The herein described frame for securing a flexible window within an opening in a curtain, the same comprising a metal strip

folded longitudinally and having one side 20 flat, the other side formed into a strip lying adjacent the first side, an outstanding shoulder forming a rabbet with said strip, and a bowed portion beyond the shoulder whose free edge constitutes a gripping jaw, means 25 for drawing this edge toward the flat side to grip the curtain, an arched strip disposed in said rabbet and adapted to overlie the window, and a fastening screw passing through this strip and the window, through 30 the strip beneath, and engaging the flat side.

In testimony whereof I affix my signature in the presence of two witnesses.

FRANK B. NIHART.
